Primary Examiner — Kelley Donnelly(74) *Attorney, Agent, or Firm* — K&L Gates LLP; Louis C. Cullman; Brian J. Novak(57) **CLAIM**

The ornamental design for a display rack, as shown and described.

DESCRIPTION

FIG. 1 is a perspective view of a display rack showing my design;

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

The broken lines are for the purpose of illustrating the environment of the article only and form no part of the claimed design.
